UNITED STATES PATENT OFFICE.

JOHN EDWARD O'CONNOR, OF SAN FRANCISCO, CALIFORNIA.

TYPEWRITING-MACHINE.

1,336,151.

Specification of Letters Patent.

Patented Apr. 6, 1920.

Application filed October 1, 1918. Serial No. 256,462.

To all whom it may concern:

Be it known that I, JOHN EDWARD O'CONNOR, a citizen of the United States, residing at 1727 Lake street, in the city and county 5 of San Francisco, State of California, have invented a new and useful Typewriting Machine, of which the following is a specification.

My invention relates to improvements in 10 typewriting machines whereby entire lines may be printed without removing the fingers from the keys.

I accomplish this:

1st. By eliminating all unnecessary characters, such as small letters or signs which can be made by the combination of other characters as, for example, the percentage sign (%) and the exclamation point (!). This leaves only fifty characters which are 20 arranged on the key board in the following order (see Figure 1, accompanying drawing):

1	\$	A	F	K	P	U	Z	:	6
2	@	B	G	L	Q	V	&	?	7
3	(	C	H	M	R	W	,	8	
4	)	D	I	N	S	X	:	"	9
5	—	E	J	O	T	Y	.	-	/

2nd. By arranging the characters on the 30 type bars or type cylinders in conformity with the type keys, as described on page 1, lines 23 to 27 inclusive of this specification. (See specimen type bar, Fig. 3 of accompanying drawing.)

3rd. In place of only one or two or three characters controlled by one key, in my invention five characters are manipulated by each key. (See Fig. 1 of accompanying drawing.)

4th. In place of only one or two or three characters on each type bar or rows on each type cylinder, my invention has five characters on each type bar and five rows of ten characters each on each type cylinder, thereby reducing the number of type bars to ten. (See Fig. 3 of accompanying drawing.)

5th. In place of small disks for keys, in my invention grooved levers adapted to the easy use of the fingers and thumbs of each hand are employed. (See No. 3, 4, 5, 6, 7, 8, 9, 10, 11, 12 of Fig. 1 of the accompanying drawing. No. 18 Fig. 2 of the accompanying drawing is a cross section of No. 5, Fig. 1.)

6th. In place of from 28 to 84 keys, my invention has only ten. (See Fig. 1 of ac-

companying drawing.) The keys are designated by the character at the top of each, thus: "1" key; "\$" key; "A" key; "F" key; "K" key; "P" key; "U" key; "Z" key; "(:)" key and "6" key and will be so designated in this specification. The fingers and thumb of the left hand are used exclusively to control keys "1"; "\$"; "A"; "F" and "K" and the thumb and fingers of the right hand are 65 exclusively used to control keys: "P", "U", "Z", "(:)" and "6". (See Fig. 1 of accompanying drawing.)

7th. By employing knobs under each palm and operated by pressing down for spacing. (See Nos. 15 and 16 of Fig. 1 of accompanying drawing. Fig. 2 under No. 18 shows a cross section of the knob.)

When the finger or thumb of one hand is engaged in striking a key, the palm of the other should be used to space.

8th. By employing the feet to raise the carriage two spaces or lower it two spaces or move it forward two spaces or backward two spaces depending on the make of the 80 machine.

Fig. 1 is a general view of the key board showing type keys, palm spacers and carriage shift keys; Fig. 2 is a cross section of a type key above a cross section of a palm 85 spacer; Fig. 3 shows a typebar; Fig. 4, the foot platform with heel and toe attachments; Fig. 5 illustrates the "operative relation of the parts," showing the slots and pulleys through which the cords or straps 90 attached to the carriage shift levers and the front and back part of the operator's feet pass.

In place of one or two shift keys worked by the finger, in my invention four shift 95 keys are attached by straps or wires to the front and back part of each foot. (See Fig. 4 and Fig. 5, showing foot apparatus and Nos. 1, 2, 13 and 14 of Fig. 1, Fig. 5, showing shift keys.) Shift keys Nos. 1 and 2 being 100 on the left side are controlled by the left foot (L, Fig. 5) and shift keys Nos. 4 and 5 being on the right side are controlled by the right foot (R, Fig. 5).

The feet rest on a platform (see Fig. 4 105 and Fig. 5 of the accompanying drawings), raised an inch or so from the floor and firmly attached thereto. The toe strap (No. 28 of Fig. 4 and No. 28 and 28a of Fig. 5) attached to the front part of each foot passes 110 down through a slot in the platform, through a pulley (27) Fig. 4 and (27) and

(27*) Fig. 5 and then up and out a few inches in front of the foot and then to its proper shift key on the typewriter which is No. 2 for the left and No. 4 for the right toe 5 (see Fig. 5).

The heel strap attached to the rear part of the foot (see #23 Fig. 4 and #23 and 23^a Fig. 5 of the accompanying drawing) also passes down into the platform, under the 10 foot, through pulleys #24 and #25 (see Fig. 4 and Fig. 5, #24 and #25 and #24^a and #25^a) and then comes out in front of the toe slot. It is then attached to its proper shift key which is No. 1 for the left 15 heel and No. 5 for the right heel.

The characters are printed in the following manner: "A," by raising left heel and pressing down "A" key; "B," by raising left toe and pressing down "A" key; "C," by 20 pressing down "A" key with feet flat on the platform; "D," by raising right toe and pressing down "A" key and "E," by raising right heel and pressing down "A" key. The other characters on the other keys are printed 25 in a similar manner, that is, all the first or top characters on the key board by raising the left heel and pressing down the key; the second character on each key, by raising the left toe and pressing down the key; the 30 third or middle character on each key, by pressing down the key with both feet flat on the platform; the fourth or next to the bottom character on each key, by raising the right toe and pressing down the key and the 35 fifth or bottom character on each key, by raising the right heel and pressing down the key.

I am aware that prior to my invention typewriting machines have been constructed 40 with typebars manipulated by finger keys and typebar levers. I am also aware that prior to my invention spacing mechanisms have been invented. I am also aware that prior to my invention typewriting machines 45 have been made with movable carriages operated by shift keys and shift levers. I therefore do not claim such a combination broadly; but

I do claim:

50 1. In a typewriting machine the combination of a foot platform with three holes or

slots in front of the spaces for the operator's feet and one hole or slot back of the spaces for the operator's feet, the fixed pulley underneath the platform and between the two 55 slots in front of and nearest the toe, the farther downward projecting fixed pulley underneath the platform and under the outermost hole or slot in front of the operator's feet, in conjunction with a strap or cord attached to a typewriter shift key or shift lever passing down through the said middle slot in the foot platform, thence through the fixed pulley underneath the platform—said pulley being placed between the two 60 65 slots aforesaid—thence and up and through the slot or hole in front of and nearest the front part of the operator's foot, to which it is adapted to be attached, substantially as described. 70

2. In a typewriting machine the combination of a foot platform with three holes or slots in front of the spaces for the operator's feet and one hole or slot back of the spaces for the operator's feet, the fixed pulley underneath the platform and between the two 75 slots in front of and nearest the toe, the farther downward projecting fixed pulley underneath the platform and under the outermost hole or slot in front of the operator's 80 feet, in conjunction with a strap or cord attached to a typewriter shift key and shift lever, passing down through the outermost of the three holes or slots in front of the operator's foot and in the said foot platform, 85 thence through the fixed and farther downward projecting pulley underneath the said platform thence through the pulley under the platform and under the operator's heel, thence up and out to the back part of the 90 operator's foot to which it is adapted to be attached, all substantially as stated.

3. In a typewriting machine the combination of a key board with typebar levers and typebars, palm spacers and shift keys and 95 shift levers attached to a movable carriage in conjunction with a foot platform with slots, pulleys and straps and attachments for the front and back part of the operator's feet, all substantially as set forth and described. 100

JOHN EDWARD O'CONNOR.
